CLAIM

I claim the ornamental design for a storage device for electronic media, as shown and described.

DESCRIPTION

FIG. 1 is a top perspective view;

FIG. 2 is a bottom perspective view;

FIG. 3 is a front plan view;

FIG. 4 is a back plan view;

FIG. 5 is a top plan view;

FIG. 6 is a bottom plan view;

FIG. 7 is a left-side view;

FIG. 8 is a right-side view;

FIG. 9 is a top perspective view of an alternate embodiment of our new design;

FIG. 10 is a front view of the alternate embodiment of FIG. 9;

FIG. 11 is a rear view of the alternate embodiment of FIG. 9;

FIG. 12 is a top plan view of the alternate embodiment of FIG. 9;

FIG. 13 is a bottom plan view of the inside of the alternate FIG. 9;

FIG. 14 is a left-side view of the alternate embodiment of FIG. 9; and,

FIG. 15 is a right-side view of the alternate embodiment of FIG. 9.

The broken lines disclaiming the compartments in the figures are for the purpose of illustrating the environment of the design only and form no part of the claimed design.
